RICHARD A. BEMIS, OF SAN BERNARDINO, CALIFORNIA.

AIR AND GAS PUMP.

1,278,572.

Specification of Letters Patent. Patented Sept. 10, 1918.

Application filed June 20, 1917. Serial No. 175,799.

To all whom it may concern:

Be it known that I, RICHARD A. BEMIS, a citizen of the United States, and resident of San Bernardino, in the county of San Bernardino and State of California, have invented a new and Improved Air and Gas Pump, of which the following is a full, clear, and exact description.

This invention relates to air and gas pumps and has particular reference to rotary pumps or analogous devices in which a piston is adapted to be rotated within a relatively stationary casing.

Among the objects of the invention is to provide a casing of peculiar construction having internal walls consisting of regular geometric forms, forms of revolution, and with a rotary piston in the casing having a plurality of blades arranged in pairs and so pivoted on axes radial with respect to the center of the piston as to swing toward and from each other and wipe against the side walls of the casing as well as filling the entire space radially between the center of the casing and the peripheral wall.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which

Figure 1 is an elevation showing a side view of the piston in place within the casing and with the greater portion of the section of the casing adjacent to the observer broken away.

Fig. 2 is a vertical longitudinal section with respect to the axis of the piston on the line 2—2 of Fig. 1.

Fig. 3 is a plan view of the device with the top portion of the casing broken away to disclose the piston within and the relation of the wings to the side walls of the casing.

Fig. 4 is a plan view of the piston in-

dicating the upper pair of wings in nested position; and

Fig. 5 is a perspective view of the piston, the wings being indicated in the same position as in Fig. 1.

Referring now more particularly to the drawings I show a casing 10 comprising two substantially similar sections 11 and 12 each having a base member 13 and a hub member 14, the base members being so arranged

as to provide or typify any suitable means for supporting the casing, and the hub members are arranged with their axes in alignment with each other and parallel to the base. Except as thus far noted the exterior of the casing is of minor consequence

except that the two sections thereof are provided with suitable means such as flanges 15 and separable fasteners 16 to secure the same together. The interior of the casing, 70

however, is to be more carefully noted. At the center of the casing the wall and hub portions are counterbored forming spherical cavities 17 both of the same size and as though formed with a common center at 18 75

which may be regarded as the actual center of the entire pump. The side wall 19 of each section of the casing is of precise conical form the apex of the cone being at the center 18, but with the heavy dotted line 80

20 representing the altitude of the cone at an oblique angle to the axis of the shaft 21 journaled in the hubs 14 and hence oblique to the median central plane of the piston which is perpendicular to said axis of the 85 shaft. In other words each side wall 19 of the casing sections may be properly described as a geometric figure of revolution around the imaginary axis 20.

The peripheral wall 22 of each casing section is at every point equally distant from the center 18 of the device and hence is a portion of a true geometric sphere and obviously said peripheral wall is parallel to the spherical socket 17 of the same section.

The piston, indicated as a whole at 23 comprises a spherical hub 24 journaled in the sockets 17 of the casing. The piston also includes what may be termed a solid or rigid disk portion comprising two parts 25 100

secured rigidly upon or formed integral with the spherical hub 24 and arranged in the same general plane and on diametrically opposite sides of said sphere. Each disk member 25 is bounded remote from the hub 24 with a periphery 26 conforming to the peripheral walls of the casing and hence of a spherical form. The advancing radial edge or end 27 of the disk member 25 may 10 be flat and described as bounded by two elements radiating from the center 18. The spherical extent of each member 25 is shown as less than 180 degrees, providing a space 28 for the wings to be described below. Considering the disk as a whole therefore and disregarding for the moment the spaces 28, it may be described as a slice from the center of the sphere and bounded on opposite sides with two conical surfaces whose apexes 20 coincide at the center of the sphere. It will thus be seen that the neck portion 29 uniting the disk members to the spherical hub 24 is materially thinner than the periphery of the piston.

25 In each space 28 I provide a pair of wings 30 each of which is pivoted on an axis radial with respect to the center 18 along one edge of the advancing end 27 of the disk member 25, the axis of each wing being indicated 30 at 31. The inner and outer ends 32 and 33 of each wing conform precisely to the spherical surfaces adjacent to which they are located and over which they glide with a fluid tight connection while the wing swings 35 around its own axis. The advancing or free edge 34 of each wing is conical and conforms to the conical surface 35 formed at the rear end or edge of the disk member 25 ahead of the same and over which said 40 edge 34 of the wing sweeps with a fairly tight contact. The coöperating surfaces 34 and 35 are portions of a true geometric cone whose altitude is the axis of the wing. Any suitable mechanical means may be provided 45 to effect the pivotal connection of the several wings to the advancing edges or ends 27 of the disk members 25 and likewise if desired suitable means such as springs 36 of any suitable nature may be arranged to 50 tend to force the wings apart or to wipe along the lateral walls 19 of the casing.

Any suitable means indicated for example as a pulley 37 connected to the shaft 21, may be provided to rotate the piston at high 55 speed. 38 and 39 represent respectively inlet and outlet means to and from the interior of the casing between the walls 19 thereof, and these ports may be arranged at any desired points circumferentially of the casing.

60 Since the walls 19 are spaced farther from each other at one side than at the other, air or other fluid admitted into the space will be gathered and compressed by the flaring

wings 30 and thereby ejected forcibly from the exit port 39. From the construction of 65 the lateral walls 19, the same being conical and with the altitude of the cone at an acute angle to the axis of the shaft 21, it follows that while the wings approach the narrower side of the casing they will be forced gradually and easily toward each other accordingly and while passing through the narrowest place the wings will lie within the lateral bounds of the disk members 25, the cross section of which is substantially the 70 same as the cross section of the narrowest space between the lateral walls of the casing. The axis of the driving shaft being inclined with respect to the axes of the lateral walls of the casing or the altitudes of 75 the cones corresponding to such walls, the spherical hub 24 serves to insure a suitable joint between the separable part of the disk or piston and the casing walls.

I claim:

1. In a rotary pump, the combination of a casing, a piston journaled for rotation therein and means to rotate the piston, said casing comprising a peripheral wall constituting a portion of a geometric sphere and a side wall of conical form, the apex of which coincides with the center of the piston, and said piston comprising a disk portion the periphery of which conforms to the peripheral wall of the casing, and also a 90 wing pivoted upon the disk portion for movement around an axis radial with respect to the center of the piston and adapted to glide along said conical lateral wall, the piston and opposite lateral wall of the 95 casing being so constructed as to coöperate with said wing to compress and force the fluid from the casing.

2. In a rotary pump, the combination of a casing, a piston journaled for rotation 105 therein and a shaft journaled in the casing to which said piston is connected, said casing comprising a peripheral wall constituting a portion of a geometric sphere whose center coincides with the center of the piston and the lateral walls of the casing bearing similar cones whose apexes coincide with the said center, but whose altitudes are similarly oblique to the axis of the piston, and said piston comprising a disk portion 110 fitted slidably between those portions of the lateral walls of the casing that are nearest to each other and movable freely through those portions of the casing where the side walls are remote from the disk, the periphery of the disk conforming to the curvature of the peripheral wall of the casing, said disk having a circumferential opening, and a pair of wings pivoted upon the radial wall 115 of said opening and movable laterally toward and from each other around axes that 120

are radial with respect to the center of the piston, the lateral edges of the wings being adapted to wipe continually over the said conical lateral walls of the casing.

5 3. In a rotary pump, the combination of a casing comprising two sections having oppositely arranged concentric spherical cavities and having lateral walls in the form of geometric cones having their apexes coin-

10 cide with said center but having their alti-

tudes oblique to each other, a piston comprising a spherical hub journaled in said cavities, said piston also including pairs of radial wings movable laterally toward and from each other and wiping over said casing walls, and means including a shaft journaled in said casing and connected diametrically with said spherical hub to rotate the piston. 15
